UNITED STATES PATENT OFFICE

134,736

DESIGN FOR A CONTAINER FOR PASTE, POWDER, AND THE LIKE

Lee M. Wiley, Marion, Ind., assignor of one-third
to Julian T. Lett and one-third to Reeley B.
Wiley, both of Marion, Ind.

Application November 11, 1942, Serial No. 108,750

Term of patent 14 years

To all whom it may concern:

Be it known that I, Lee M. Wiley, a citizen of the United States of America and a resident of Marion, county of Grant, and State of Indiana, have invented a new, original, and ornamental Design for a Container for Paste, Powder, and the like, of which the following is a specification, reference being had to the accompanying drawing, forming part thereof.

Fig. 1 is a top plan view of a container, for paste, powder and the like, showing my new design.

Fig. 2 is a side elevational view.

Fig. 3 is a diametral sectional view.

Fig. 4 is a top plan view of the lower portion only thereof.

The dominant features of my design reside in the portions shown in full lines in the drawing.

I claim:

The ornamental design for a container for paste, powder, and the like, substantially as shown and described.

LEE M. WILEY.
